UNITED STATES PATENT OFFICE.

MICHAEL F. BROGAN AND JAMES A. BROGAN, OF LAWRENCE, MASSACHUSETTS, AS-
SIGNORS TO UNITED SHOE MACHINERY CORPORATION, OF PATERSON, NEW JER-
SEY, A CORPORATION OF NEW JERSEY.

SHOE AND METHOD OF MAKING THE SAME.

Application filed April 14, 1919. Serial No. 289,906.

To all whom it may concern:

Be it known that we, MICHAEL F. BROGAN and JAMES A. BROGAN, citizens of the United States, both residing at Lawrence, in the 5 county of Essex and State of Massachusetts, have invented certain new and useful Improvements in Shoes and Methods of Making the Same; and we do hereby declare the following to be a full, clear, and 10 exact description of the invention, such as will enable others skilled in the art to which it appertains to make and use the same.

This invention relates to shoes and the method of making them, and more particularly to the manufacture of turn shoes.

From time to time the styles of shoes change and periodically there is a large demand for shoes made on an extremely narrow toed last, such as was the vogue two 20 decades ago. To build a shoe on these narrow toed lasts it is necessary to shape the sole with a much more pointed toe than has generally been in use such soles being known to the trade as "peaked-toe soles." To produce these soles many changes have been made in the sole fitting machines and in incorporating them in the shoe difficulty has been experienced in sewing around their peaked toes. It has been found that the 30 operators of the inseaming machines are not permitted, by reason of the narrow space at the extreme point of the toe, to sew down the advance side of the toe with stitches that are inserted, as they should be, at right angles to the line of feed. Consequently, in order to give room for the strokes of the awl and needle the shoe is swung somewhat before it ought to be. As a result the stitches are distorted and the between substance weakened to such an extent that the shoe rips at the toe before its completion causing a cripple. This is particularly true in making turn shoes because the step of turning them right side out places a particularly severe strain on the inseam at the toe. Such cripples require the extra expense of cobbling before they can be marketed.

The object of the present invention is to 50 eliminate the conditions which cause ripping of the inseam as just described, and thus avoid the production of cripples and consequently the additional expense incurred in cobbling them.

Accordingly the present inventors have 55 conceived a novel construction of shoe and method of making it which will insure a secure attachment of the upper about peaked-toe soles of the present styles, an important feature of which resides in an improved inseam, which will be explained in the following specification and then pointed out in the appended claims.

The preferred construction of the shoe and the method of making it is illustrated 60 in the accompanying drawing in which, Figure 1 is a perspective of a peaked-toe turn shoe, after the present novel inseaming operation has been performed but before the upper has been turned; Fig. 2 is a perspective of the novel turn sole which is incorporated in the shoe shown in Fig. 1; and Fig. 3 is a cross section through the inseam at the toe.

In constructing the shoe illustrated in the 65 drawings, the upper 10 is made in any of the usual styles and is assembled on the last in the usual way, wrong side out (see Fig. 1). The sole 12, however, has a distinctly novel feature shown to better advantage by Fig. 2. In fitting the turn sole 70 the usual marginal channel cut 14 is made, but instead of fitting the sole with a continuous shoulder throughout the shank and forepart, there are provided shoulders 16 and 18 at the sides of the sole, each of 75 which terminates about one and one half inches to the rear of the tip of the toe. Between the forward ends of these shoulders and joining them about the toe end of the sole is a lip 20. This lip may be formed by 80 leaving the string of sole material, ordinarily separated from the sole by the shoulder knife, attached to the between substance. The lip 20 is then raised and set in an up- 85 standing position, as shown by Fig. 2, so that finally a continuous marginal shoulder 90 is obtained, one portion having its original height and thus being of the usual form but the toe portion being formed by the upstanding lip. This sole is assembled on the last with the upper, which latter is lasted 95 into position over the margin 22 outside the shoulder by means of any of the lasting machines now in use.

After the shoe has been lasted the upper is 100 secured to the sole in the novel manner now to be described. Preferably the shoe is first

taken to an inseaming machine of suitable design, any of the usual inseaming machines now in use being entirely satisfactory, and the upper is stitched in the usual manner along the shank, on each side, and also along the forepart as far forward as the rear ends of the lip 20. In other words the shoe is inseamed with a sewed seam throughout the extent of the old shoulder fitting, as shown at 24 in Fig. 1, but at the toe, where the trouble with a sewed seam has heretofore occurred, this seam is discontinued and a different type of fastening device is employed which is so selected as to insure a tight inseam under the strain to which this portion of the shoe is subjected, and particularly the strain of the shoe turning operation.

The fastening device at the toe forms an important feature of the present invention and practice has determined that while a continuous or connected fastening is satisfactory at the rear of the toe it is more advantageous to employ separated fasteners at the toe, for example, wire staples. The stapling at the toe is performed as a separate operation and by preference a machine of the type disclosed in Letters Patent of the United States to William J. Kelly, No. 1,214,317 dated January 30, 1917, is used. This machine drives staples 26 as the lasted shoe is fed past its staple forming mechanism, while simultaneously a reinforcing cord 28, as described in the patent, is fed into the angle of the shoulder, over which cord the staples are driven. It is to assist, and make secure, this stapling operation that the lip 20 is formed at the toe of the sole. This lip provides a higher shoulder than is offered when the usual shoulder cut is made, thus enabling the increased thickness of the upper materials at the toe to be properly lasted in position for permanent securement, and eliminates the former tendency of the stapling machine to drive the staple high. The anvil of the stapling machine is entered in the channel, as disclosed in Letters Patent of the United States to John W. Cosgrove, No. 1,250,285 dated December 18, 1917, and the lip 20 offers such additional support to the upper materials at the toe that the staples may be driven through the between substance and successfully clenched, as illustrated by Fig. 3 of the drawing hereto attached. Moreover, such weakening of the between substance as is above explained is avoided because the staples are distinct from each other and may be inserted at such points and at such distances apart as are deemed best for the particular work in hand inasmuch as, in the type of stapling machine employed, the spacing is done by the operator and is not automatic or predetermined.

The inventors believe themselves to be the first to construct a turn shoe, of the pre-

vailing peaked-toe style, in such manner that a secure fastening is obtained at the toe thereof, but it should be understood that the novel inseam described is not limited to use in that style alone, nor to turn shoes alone, although it is of particular advantage in turn shoes where a greater strain is placed upon the toe during the manufacture of the shoe than is encountered in manufacturing other types of shoes.

The nature and scope of the invention having been indicated and a shoe constituting the preferred embodiment thereof and a method of manufacturing such a shoe having been specifically described, what is claimed as new, is:—

1. A shoe having the upper thereof secured to a channeled sole by an inseam comprising at each side of the sole a single, continuous thread seam terminating near the tip line, and a series of separate fastenings extending through the between substance forward of that line.

2. A shoe comprising an upper, a sole having inner and outer channels forming a between substance, and an inseam constituting the permanent connection between the upper and the sole extending through the between substance substantially parallel to the face of the sole and comprising a single, continuous thread seam at each side of the sole which terminates near the tip line, and a series of metallic staples around the toe.

3. A shoe comprising an upper; a sole having a marginal lip about its toe end, a marginal shoulder along its sides and a marginal channel within said lip and shoulder forming a between substance; a continuous fastening element securing said upper to the between substance except along said lip; and separated fasteners securing said upper to the between substance along said lip.

4. The method of making shoes which includes the steps of assembling a channeled sole and an upper, and of permanently securing the upper to the sole by stitching through its between substance along each side of the sole to a point near the tip line, and stapling about the toe through the between substance of the sole between the ends of the stitched seams.

5. The method of making shoes which includes the steps of preparing the sole with a marginal lip about the toe end and a marginal shoulder without a lip extending rearwardly from the ends of said lip; assembling an upper with said sole; and securing the upper to the sole by a sewed seam along the shoulder and by individual fasteners along the lip.

6. The method of making shoes which comprises preparing a sole with a marginal channel throughout the shank and forepart, a shoulder extending parallel to said chan-

nel for a portion of its length, and a lip extending parallel to another portion of the channel; assembling said sole with an upper; and securing said sole and upper together by different types of fastenings extending into the channel through said shoulder and lip respectively.

5. The method of making shoes which comprises preparing a sole having a marginal lip at its toe, a marginal shoulder extending rearwardly from each end of said lip, and a channel parallel to both lip and shoulder; assembling said sole with an upper; and securing said sole and upper together by a sewed seam along said shoulder and by staples along said lip.

10. A sole for shoes having a marginal channel throughout the shank and forepart, a shoulder extending parallel to said channel for a portion of its length, and a lip extending parallel to another portion of the channel.

15. A sole for shoes having a marginal lip about its toe end, a marginal shoulder ex-

tending rearwardly from each end of said lip, and a marginal channel parallel to both lip and shoulder.

10. A turn shoe having the upper thereof secured to a channeled sole by a single series only of connected fasteners at each side of the sole and by another single series only of separated fasteners at the toe portion thereof.

11. A turn shoe having the upper thereof secured to a channeled sole by staples at the toe portion of the sole and by a series of fasteners of a different kind at the sides of the sole, and having a reinforcing cord straddled by said staples.

12. That method of making shoes which comprises assembling a channeled sole and an upper, permanently securing the upper to the sole by stitching through the between substance thereof and inserting metallic fasteners about the toe only through the be- 45
